DESIGN FOR A TUB OR SIMILAR RECEPTACLE

Herman Berard, Winchendon, Mass., assignor to
William Brown & Sons Company, Winchendon,
Mass., a corporation of Massachusetts

Application June 22, 1933. Serial No. 48,494

Term of patent 14 years

To all whom it may concern:

Be it known that I, HERMAN BERARD, a citizen of the United States, residing at Winchendon, in the county of Worcester and State of Massachusetts, have invented a new, original, and ornamental Design for a Tub or Similar Receptacle, of which the following is a specification, reference being had to the accompanying drawing, forming part thereof.

Fig. 1 is an elevation partly in section, and Fig. 2 is a plan, showing my new design.

I claim:

The ornamental design for a tub or similar receptacle as shown.

HERMAN BERARD.
